GAME BOARD

Robert W. Dervishian, Richmond, Va., assignor to Chess, Inc., Richmond, Va.

Filed July 29, 1971, Ser. No. 167,543

Term of patent 14 years

Int. Cl. D21—01

U.S. Cl. D34—5

Fig. 1

Fig. 2

FIG. 1 is a top plan view of a game board showing my new design; and

FIG. 2 is a side elevation of one of the sides of the game board.

The sides not shown are the same as those shown in FIG. 2. The bottom of the game board is planar and has no design features.

The drawing is lined for color.

I claim:

The ornamental design for a game board, as shown and described.
